FIG.4.

Inventor
SAMUEL RUBEN

By his Attorney Mr. C. Clephane

UNITED STATES PATENT OFFICE

SAMUEL RUBEN, OF NEW YORK, N. Y., ASSIGNOR TO RUBEN PATENTS COMPANY, OF NEW YORK, N. Y., A CORPORATION OF DELAWARE

MICROPHONE

Application filed October 15, 1928. Serial No. 312,683.

This invention relates to an electric microphone and more particularly it relates to a microphone functioning through contact resistance variations with pressure changes upon a surface composed of cuprous oxide in contact with another electrode. The object of the invention is the provision of a device of this character which operates with maximum sensitivity and which is durable and low in cost of construction.

I have found that the contact resistance of cuprous oxide sensitively varies with the pressure applied to its surface and that this material can be used particularly advantageous-
ly in an electric circuit to modulate a current when sound waves are impressed upon a contacting electrode, also in producing audio frequency oscillations in a circuit inductively related to a microphone employing an electrode coated with cuprous oxide and connected in a direct current circuit.

It is desirable to have a wide contacting surface area between the electrodes, the applied physical energy effecting substantially no change of contacting area but varying the inter-molecular contact at the junction between one electrode and another having the cuprous oxide layer, and causing a change in contact resistance of this material. For effective operation the oxide coating must be of a homogeneous, non-porous, dense, crystalline character integrally formed with the base material.

For a better understanding of this invention reference is made to the accompanying drawings in which Fig. 1 represents a graph of the electrical relation between the pressure applied to and the contact resistance of an electrode composed of copper with the cuprous oxide layer contacting with another electrode. Fig. 2 shows one embodiment of the invention in the form of a microphone having an electrode composed of a copper base with a layer of cuprous oxide contacting with another electrode. Fig. 3 shows the same microphone arrangement connected with an electromagnet. Fig. 4 outlines a circuit in which this latter device is connected.

Referring more particularly to Fig. 2, 1 represents a steel diaphragm as one electrode,

2 a stationary copper electrode the surface of which is composed of a layer of fused cuprous oxide 3, electrode 1 and the cuprous oxide electrode being in contact over the entire adjacent surface area of the latter. These 55 elements are enclosed in and supported by insulating members 5 and 6. The copper electrode 2 is mounted on screw 4 supported in insulation member 6. A metal case 9 is used for enclosing the several elements and the terminals of the two electrodes are respectively at 7 and 8.

In the arrangement shown in Fig. 3 a microphone is arranged to continuously produce electrical oscillations of audio frequency from 65 a direct current. On the side of diaphragm 1, opposite that of the cuprous oxide layer 3, is arranged an electromagnet which can influence the position of steel diaphragm 1. The primary and secondary windings of the electromagnet are represented respectively at 10 and 11, the primary being connected to diaphragm 1 by lead 1_a and to the insulated electrode terminal 7 in the direct current supply 70 circuit. The secondary winding is connected to two insulated terminals, 11_a and 11_b. In Fig. 4, G represents a direct current generator.

In operation of the microphone as shown in Fig. 2, the initial resistance of the device is 80 the sum of the contact and internal resistances; but as pressure is applied to the contact area, the resistance at the juncture between diaphragm 1 and the cuprous oxide layer 3 decreases, permitting a corresponding increase of current flow through the device.

In the operation of the device as shown in Fig. 3, as direct current is applied to the terminals 7 and 8, current flows through the contact between the electrodes 1 and 2, and 90 the electromagnetic primary coil 10. As this coil is energized diaphragm 1 is drawn toward the electromagnet, thereby reducing the pressure between the diaphragm 1 and the cuprous oxide layer 3, and increasing the 95 contact resistance to the flow of current through this circuit, causing a decrease in the direct current flow. The effect of such decreased current flow is that the diaphragm 100 by its spring pressure returns to its close con-

tact with surface 3, thereby increasing the contact pressure between the diaphragm and the oxide surface and again permitting an increased flow through the direct current circuit. This cycle of action is continuously maintained, thereby producing a vibratory movement of the diaphragm of audio frequency. By reason of the field changes in the primary, there is induced in the secondary 5 winding a potential of the frequency maintained by the oscillating diaphragm. Used as an oscillator, power of considerable magnitude and frequency, as in the order of 1000 cycles, has been maintained without difficulty over long periods.

With a disc electrode, having a contact area with a fused cuprous oxide electrode of .5 square inches and initially in complete surface contact therewith, the resistance change 10 with pressure from 0 to 100 pounds was from 15,000 to 50 ohms.

Microphones constructed as here described show a sensitivity well beyond that of any of the devices known in the prior art; they are 15 capable of modulating powers of much greater values without the limitations due to thermal effects, as commonly experienced in the carbon type of microphone.

What I claim is:

30 1. A microphone having as one of its pressure operative electrodes a copper body having on its surface a layer of a homogeneous, nonporous, dense, crystalline compound of copper integrally formed with the copper 35 body.

2. A device for translating audio frequency oscillations into oscillations of like frequencies in an electric circuit, which comprises a vibratory electrode, in surface contact with a cuprous oxide cooperating electrode, means for directing audio frequency oscillations upon one of said electrodes and means for supporting and protecting said electrodes from extraneous audio frequency 40 oscillations.

3. A device for translating sound waves into oscillations of like frequencies in an electric circuit, which comprises a vibratory electrode, in surface contact with a cuprous oxide 45 cooperating electrode, means for directing sound waves upon the first mentioned electrode, means for supporting and protecting said elements from extraneous sound waves and means for oscillating the vibratory electrode by impressing thereon audio frequency oscillations from an electromagnet, the energizing current for said device being controlled by the movement of said vibratory electrode.

60 4. A device for translating sound waves into electrical oscillations of like frequencies, which comprises a vibratory electrode in surface contact with a cooperating cuprous oxide electrode, means for supporting and shielding 65 said electrodes from extraneous sound

waves, and means for oscillating the vibratory electrode by impressing thereon audio frequency oscillations from an electromagnet.

In testimony whereof, SAMUEL RUBEN has signed his name to this specification this 8th day of October 1928.

SAMUEL RUBEN.
